Primary Examiner — Rosemary K Tarcza*(74) Attorney, Agent, or Firm* — Ohlandt, Greeley,
Ruggiero & Perle, LLP(57) **CLAIM**

The ornamental design for a tobacco suction tool battery, as shown and described.

DESCRIPTION

FIG. 1 is a perspective view from the left side of a tobacco suction tool battery.

FIG. 2 is a perspective view from the right side thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is an enlarged perspective view thereof; and,

FIG. 10 is an enlarged cross-sectional view taken along the line 10-10 in FIG. 7, which omits the internal structure thereof.

The broken lines shown in the drawings illustrate portions of the tobacco suction tool battery that form no part of claimed design.

1 Claim, 10 Drawing Sheets(56)
